(57) **CLAIM**

The ornamental design for a flexible tube for hand-operated male masturbation device, as shown.

DESCRIPTION

FIG. 1 shows the right side view of a first embodiment of my new design.

FIG. 2 shows the top view of the tube of a first embodiment of my new design.

FIG. 3 shows the left side view of a first embodiment of my new design.

FIG. 4 shows the bottom view of a first embodiment of my new design.

FIG. 5 shows the left end view of a first embodiment of my new design.

FIG. 6 shows the right end view of a first embodiment of my new design.

FIG. 7 shows the top perspective view of a first embodiment of my new design.

FIG. 8 shows the right side view of a second embodiment of my new design.

FIG. 9 shows the top view of the tube of a second embodiment of my new design.

FIG. 10 shows the left side view of a second embodiment of my new design.

FIG. 11 shows the bottom view of a second embodiment of my new design.

FIG. 12 shows the left end view of a second embodiment of my new design.

FIG. 13 shows the right end view of a second embodiment of my new design; and,

FIG. 14 shows the top perspective view of a second embodiment of my new design.
